UNITED STATES PATENT OFFICE.

VINCENT G. ANDERSON, OF PITT, MINNESOTA, ASSIGNOR TO FREDERICK C. AUSTIN, OF CHICAGO, ILLINOIS.

EXCAVATOR OR OTHER SUPPORTING MEANS.

Application filed October 21, 1918. Serial No. 259,008.

To all whom it may concern:

Be it known that I, VINCENT G. ANDERSON, a citizen of the United States of America, and a resident of Pitt, Minnesota, have 5 invented a certain new and useful Improvement in Excavators or Other Supporting Means, of which the following is a specification.

This invention relates to means for supporting excavators or other heavy bodies on the ground, and more especially to those which travel ahead of the excavation, such, for example, as drag-line excavators, and other similar excavating machines requiring strong and substantial supporting means.

The object of the invention is to provide a novel and improved construction and arrangement whereby the excavator or other 20 heavy body will be firmly supported when shifted ahead over uneven ground, whereby breakage or straining will be less liable to occur.

It is also an object to provide certain 25 details and features of construction tending to increase the general efficiency and serviceability of supporting means of this particular character.

To these and other useful ends the invention consists in matters hereinafter set forth and claimed.

In the accompanying drawings—

Fig. 1 is a plan of a drag-line excavator body equipped with supporting means involving the principles of the invention.

Fig. 2 is a side elevation of the structure shown in Fig. 1.

Fig. 3 is an enlarged detail section on line 3—3 in Fig. 2.

Fig. 4 is a vertical section on line 4—4 in Fig. 3.

As thus illustrated, the invention comprises a rectangular body frame having sides 1 and front and rear ends 2 and 3. The 45 propelling apparatus or means for moving the excavator forward from time to time may be of any suitable character. A boom 4 is mounted in the usual or any suitable manner on the rear end of the body frame. The excavating apparatus may comprise a drag-line bucket (not shown) or any other 50 suitable or well known means.

The supporting means are as follows:

The rear end of the body frame is provided with rigid legs 5 at each corner of the

frame, and broad shoes or runners 6 are provided to support said legs on the ground. Each leg has a joint, such as a double pivot, at its lower end, of any suitable character which permits the shoe or runner to tilt or 60 rock sidewise, as well as to tilt up and down at its front and rear ends. In this way each shoe or runner can accommodate itself to uneven ground without danger of breakage. These joints have been used before, 65 and may be of any ordinary or suitable character. At the front end of the body frame the third leg 7 is in the center and is pivoted on the frame at 8, so that the frame may rock sidewise about the longitudinal 70 axis formed by said pivot. At its lower end the leg 7 is pivoted at 9 on the shoe or runner 10, whereby the latter may tilt endwise only—that is to say, can only tilt up and down at its front and rear ends, and does 75 not tilt sidewise relatively to the leg; but the pivot 8 permits the runner 10 to tilt sidewise relatively to the body frame. Preferably, the lower ends of the legs 5 and 7 have a sort of ball and socket pivot with the 80 shoes, so that the loose pivots do not sustain the weight.

Thus the body frame has a three-point bearing, so to speak, being supported at two points in the rear and at one point in front, 85 whereby the excavator may be shifted around over uneven ground with less danger of twisting the frame, or of straining the other parts, and with less danger of breakage than heretofore. The three shoes or 90 runners will always rest on the ground, even when traveling over uneven surfaces, and thus the excavator will be steady and will be firmly supported at all times.

The shoes or runners can be of any suitable, known, or approved construction, and these slide on the ground when the excavator or other heavy body is propelled or pulled forward. With excavators of this kind, it is common to use a propelling apparatus of the kind which has a walking movement (not shown), so that the body of the excavator is alternately raised and lowered, being lifted or partially lifted, while moved forward. This is well understood, 100 however, and no illustration or further explanation is required. With the body of the excavator supported at only one point at the front but at two points at the rear, the danger of twisting or straining the body 110

frame or other parts of the structure is practically reduced to a minimum, but at the same time the body is substantially and firmly supported, so that it will not wabble or teeter while the excavating apparatus is in operation. At the same time, however, the shoes or runners can tilt around and automatically adjust themselves to uneven ground surfaces, but with only three shoes 10 or runners, arranged as shown, and with the longitudinal center pivot for the upper end of the front leg, the shoes or runners will all rest on the ground under all conditions and regardless of the uneven character 15 of the ground surface.

What I claim as my invention is:—

1. In an excavator, a body frame, three sliding supports which give said body frame a three-point bearing on the ground, and 20 means to support the body frame on said supports, whereby each support is self-adjusting under said frame, including provisions whereby one end of the body frame

rocks about a longitudinal axis on the upper end of one of said supports, so that the 25 body frame has a three-point bearing with the single or third bearing higher than the other two on said supports.

2. A structure as specified in claim 1, said means including transverse pivots for said 30 supports, whereby said supports are each free to rock about an axis extending at right angles to said longitudinal axis.

3. A structure as specified in claim 1, said provisions comprising a leg pivoted at its 35 upper end on the body frame, thereby to form said longitudinal axis, and pivoted at its lower end to provide a transverse axis for said one support, a pair of rigid legs for said body frame, and means at the lower 40 ends of said rigid legs to allow free tilting of the other supports about both transverse and longitudinal axes, thereby to permit self adjustment of the supports on the ground.

VINCENT G. ANDERSON.
